(57) **CLAIM**

The ornamental design for an adjustable bed, as shown and described.

DESCRIPTION

FIG. 1 shows a perspective view of the present design. FIG. 2 shows a front view of the present design; and, FIG. 3 is a schematic drawing showing that the adjustable bed of the present design is adjusted to a flat posture. The broken lines showing of structural feature is indeed for the purpose of illustrating non-claimed subject matter and forms no part of the claimed design.

1 Claim, 3 Drawing Sheets

FIG. 1

FIG. 2

FIG. 3
